(57) **CLAIM**

The ornamental design for a container for transporting heated food, particularly pizza and the like, as shown and described.

DESCRIPTION

FIG. 1 is a perspective view from above—closed container—of a container for transporting heated food, particularly pizza and the like and shows our design;

FIG. 2 is a perspective view from above—partially open container—of the container for transporting heated food, particularly pizza and the like;

FIG. 3 is a perspective view from above—fully open container—of the container for transporting heated food, particularly pizza and the like;

FIG. 4 is a perspective view from below—fully open container—of the container for transporting heated food, particularly pizza and the like;

FIG. 5 is a top plan view—closed container—of the container for transporting heated food, particularly pizza and the like;

FIG. 6 is a rear side view—closed container—of the container for transporting heated food, particularly pizza and the like;

FIG. 7 is a bottom plan view—closed container—of the container for transporting heated food, particularly pizza and the like;

FIG. 8 is a front side view—closed container—of the container for transporting heated food, particularly pizza and the like;

FIG. 9 is a right side view—closed container—of the container for transporting heated food, particularly pizza and the like; and,

FIG. 10 is a left side view—closed container—of the container for transporting heated food, particularly pizza and the like.
